Des. 234,666
Patented Apr. 1, 1975

234,666

COFFEE PERCOLATOR

Thomas E. Hanson, Philadelphia, Pa., assignor to
SCM Corporation

Filed Sept. 17, 1973, Ser. No. 398,036

Term of patent 14 years

Int. Cl. D7—02

U.S. Cl. D7—62

FIG. 1 is a front perspective view of a coffee percolator showing my new design;

FIG. 2 is a rear perspective view thereof;

FIG. 3 is a top plan view thereof;

FIG. 4 is a side elevational view thereof; and

FIG. 5 is a bottom plan view thereof.

I claim:

The ornamental design for a coffee percolator, as shown.
